UNITED STATES PATENT OFFICE.

CHARLES C. HANSEN, OF EASTON, PENNSYLVANIA, ASSIGNOR TO INGERSOLL-RAND COMPANY, OF NEW YORK, N. Y., A CORPORATION OF NEW JERSEY.

ROTATION RELEASE FOR ROCK DRILLS.

Application filed July 23, 1920. Serial No. 398,372.

To all whom it may concern:

Be it known that I, CHARLES C. HANSEN, a citizen of the United States, residing at Easton, in the county of Northampton and 5 State of Pennsylvania, have invented certain new and useful Improvements in Rotation Releases for Rock Drills, of which the following is a specification.

This invention relates to rock drills of the 10 hammer type having automatic rotation for the drill steel, as for instance rifle bar rotation, but relates more particularly to a device for releasing the rotation when desired.

The primary object of the invention is to 15 enable the operator to change from a positive rotation to a slip rotation at will, as for instance in hard ground.

If the drill steel sticks it may be desirable 20 to release the positive rotation and permit the hammer to operate with the slip rotation or operate without rotating the drill steel, until the normal positive rotation can be resumed, and my rotation releasing device accomplishes these objects in a simple and efficient 25 manner without complication of the parts.

To these ends the invention is shown in one of its preferred forms in the accompanying drawings, in which—

Figure 1 is a longitudinal sectional elevation 30 of a rock drill containing the device,

Figure 2 is a longitudinal detail sectional elevation taken through the rear end of the piston hammer partly in perspective, and

Figure 3 is a transverse sectional view on the line 3—3 of Figure 1 looking in the direction of the arrows.

In order to illustrate the invention a fluid 40 pressure actuated rock drill of the hammer type having a rifle bar rotation is illustrated, only so much of the operative parts being shown as will serve to make the invention clear, the ports and passages for the distribution of motive fluid to the hammer cylinder being omitted as forming no part of the present invention.

Referring to the drawings, the drill cylinder A is mounted on the shell B in the usual manner. The machine is fed to its work by means of the feed screw C having the feed screw nut D, the feed nut locknut E and the feed crank F.

Fluid pressure is admitted to the drill cylinder A and its operative parts from the

inlet G and exhausted at the outlet H for 65 operating the piston hammer J reciprocating within the cylinder. The drill steel K is carried in the chuck or rotation sleeve L within the front head O and the forward extension of the shank P of the piston hammer is provided with the straight flutes Q 70 engaging corresponding grooves in the rotation sleeve L. In this instance a front cylinder washer or piston bearing R is located at the front end of the cylinder and forms 75 a guide for the piston shank.

The rearward reduced extension of the shank S of the piston is hollow and internally fluted with spiral flutes T engaging the rifle bar U having a head V held between the rotation washer W and the back head X of the machine. The rifle bar head V is provided with the rotation pawls Y 80 adapted to engage the teeth of the rotation ratchet ring Z, which is adapted to be held 75 from rotation by means of the rotation releasing device a preferably in the form of a pin slidable into and out of engagement with the ratchet rotation ring Z.

The ratchet ring Z is preferably provided 85 with a recess b in its periphery, adapted to register with the recesses c and d in the cylinder A and back head X respectively of the machine. The pin a is conveniently arranged to slide longitudinally into the back 90 head X and is provided with a cylindrical enlargement or head e for engaging the ratchet ring Z. Engagement between the back head X, ratchet Z and cylinder A by the pin a having the enlargement e is thus 95 effected at the point of juncture of all these parts, locking the back head X and ratchet Z together by a single means at a common point. A spring f is adapted to be compressed between the head e of the pin and a shoulder g in the aperture h within which the head e slides. The pin a is also provided with a handle or button j and a stop k provided on the shank of the pin enters the groove o when the pin is in locking position 100 as indicated in Figure 2. When the pin is withdrawn to release the rotation as indicated in Figure 1, the stop pin k is rotated and may lie against the back head to hold the pin in withdrawn position.

In the operation of the device the drill steel is rotated through the rifle bar rotation in this instance on the back stroke or up

2

stroke of the piston and this is a positive rotation when the pin *a* is in locking position as indicated in Figure 2 because the rifle bar *U* is then held stationary as the 5 rotation ratchet ring *Z* cannot turn. In case it is desired to change from positive to slip rotation, the pin *a* is withdrawn into the position indicated in Figure 1 thus releasing the rotation and permitting the 10 rotation ratchet ring *Z* to slip or rotate relatively to the drill casing. There may be a partial slip in which case there will be a partial rotation of the drill steel, but in case the resistance to rotation in hard ground is 15 sufficient to overcome the frictional engagement between the rotation ratchet ring and the parts between which it is held, the hammer will operate without rotating the drill steel. The rotation releasing pin *a* is again 20 moved into engagement with the rotation ratchet ring when normal positive rotation is to be resumed.

I claim:

- 25 1. A rock drill of the hammer type having rifle bar rotation for the drill steel including a drill casing, a back head a rotation ratchet ring having a recess in its periphery adapted to register with a locking recess in the drill casing, a spring 30 pressed pin carried in the back head in longitudinal alignment with the drill casing, said pin adapted to enter said recesses and engage said ratchet ring, casing and back head at a point of juncture of said ratchet 35 ring, casing, and back head for producing positive rotation of the drill steel, but removable therefrom to release the rotation and permit slip of the ratchet ring relative to the drill casing.
- 40 2. A rock drill of the hammer type hav-

ing rifle bar rotation for the drill steel including a drill casing, a back head a rotation ratchet ring having a recess in its periphery adapted to register with a locking recess in the drill casing, a spring 45 pressed pin mounted in the back head and a cylindrical enlargement at the end of said pin adapted to enter said recesses and engage said ratchet ring, casing and back head 50 at a point of juncture of said ratchet ring, casing and back head for producing positive rotation of the drill steel, but removable therefrom to release the rotation and permit slip of the ratchet ring relative to the 55 drill casing, and means for maintaining said pin in withdrawn position.

3. A rock drill of the hammer type having rifle bar rotation for the drill steel, a cylinder casing, a back head for the casing, 60 said rifle bar rotation including a rotation ratchet ring having a recess in its periphery adapted to register with a locking recess in the interior of the cylinder casing 65 a recess in said back head, and a spring 70 pressed pin carried in said recess being in longitudinal alignment with the drill casing and having a cylindrical head at its inner end adapted to enter said registering recesses in the ratchet ring and cylinder casing at the point of juncture of 75 said parts for producing positive rotation of the drill steel, means for withdrawing the pin into the back head to release the rotation and permit slip of the ratchet ring relative to the drill casing, and means for locking said pin in retracted position.

In testimony whereof I have signed this specification.

CHARLES C. HANSEN.
